HELICOPTER WITH ONE OR MORE ROTORS
HAVING CONTROLLABLE AILERONS

Fred Landgraf, Los Angeles, Calif.

Application December 8, 1942, Serial No. 468,196

7 Claims. (Cl. 244—17)

1

This invention relates to airplanes, and particularly to helicopters.

Such airplanes are characterized by the provision of one or more air screws or rotors having axes of rotation substantially vertical. Suitable rotation of the air screws thus produces air reactions on the airscrew blades such that the resultant of the air forces is substantially vertical and opposite to the force of gravity. Properly controlled and directed, this force may be used to raise or lower the helicopter at a steep angle, or to cause it to move sideways, backward or forward either slowly or at high speed.

It is one of the objects of this invention to improve in general, airplanes of this character. In this connection, control of the helicopter is attained by control of the pitch of the air screw, or by control of ailerons carried by the blades of the rotor or screw.

As heretofore mentioned, the wings or blades of the helicopter rotor are each provided with an aileron on its trailing edge. These ailerons are so arranged that they may be maintained in a fixed position with respect to the blade. However, by the aid of a control mechanism, it is optionally possible to cause the ailerons to move through a cycle, so that for each revolution of a rotor, the ailerons of all the blades attain a maximum departure from neutral at any desired position of the blade in its rotating cycle. The amplitude of the aileron motion as well as the cyclic position of the blade where aileron displacement is maximum are both under the control of the pilot. By appropriate joint control of the ailerons of both rotors, the air forces on the blades may be modified so as to produce rolling or pitching moments or combinations thereof in addition to the vertical lifting force previously mentioned. The resultant effects upon the direction of flight of the helicopter are well-known to a pilot; it is sufficient herein to point out the features of the aileron controls.

It is another object of this invention to provide a simple and thoroughly reliable control for operating the ailerons; and in this connection it is still another object of the invention to make it possible to test the aileron controls when the helicopter is grounded.

This invention possesses many other advantages, and has other objects which may be made more easily apparent from a consideration of one embodiment of the invention. For this purpose there is shown a form in the drawings accompanying and forming part of the present specification. This form will now be described in de-

2

tail, illustrating the general principles of the invention; but it is to be understood that this detailed description is not to be taken in a limiting sense, since the scope of this invention is best defined by the appended claims.

Referring to the drawings:

Figure 1 is an elevation of a helicopter incorporating the invention, part of the fuselage being broken away, and the disposition of the 10 control operating parts, and of the power drive, of the helicopter being illustrated in diagrammatic form within the main outline of the fuselage;

Fig. 2 is a top plan view of the helicopter illustrated in Fig. 1;

Fig. 3 is an enlarged sectional view taken along the plane 3—3 of Fig. 2;

Fig. 4 is a sectional view taken along plane 4—4 of Fig. 3;

20 Figs. 5 and 6 are detail sectional views on an enlarged scale, taken along the correspondingly numbered planes of Fig. 3;

Fig. 7 is an enlarged fragmentary elevation, partly broken away, looking in the direction of 25 the arrow 1 of Fig. 3;

Fig. 8 is a fragmentary view of one of the rotors, only one of the rotor blades being shown completely, the other two rotor blades being broken away, the rotor shown in this figure being 30 the one disposed on the left hand side of the helicopter;

Figs. 9 and 10 are horizontal views, mainly in section, of one of the rotor blades taken through the axis of the spar upon which the 35 blade is supported; the blade chosen in this instance being the blade shown in Fig. 8;

Figs. 11, 12, 13 and 14 are sectional views taken along correspondingly numbered planes of Fig. 9;

40 Fig. 15 is a sectional view taken along plane 15—15 of Fig. 10;

Fig. 17 is a horizontal section taken along plane 17—17 of Fig. 16, with the supporting spar removed;

50 Figs. 18 and 19 are plan views of the spring hinge members adapted to cooperate to support a blade adjustably with respect to its supporting spar;

Fig. 20 is a fragmentary cross section, on an 55 enlarged scale, through a rotor blade showing the

action of the hinge members illustrated in Figs. 18 and 19;

Fig. 21 is a fragmentary plan view, partly in section, of the outer end portion of a rotor blade such as illustrated in Fig. 8, part of the figure being broken away and illustrating the mechanism for controlling the aileron;

Figs. 22, 23, 24 and 25 are fragmentary sectional views on an enlarged scale, taken along the correspondingly numbered planes of Fig. 21;

Fig. 26 is a detail sectional view taken along the plane 26-26 of Fig. 22;

Fig. 27 is a vertical section taken along the plane 27-27 of Fig. 2, a portion of the body of the helicopter being removed;

Figs. 28 and 29 are sectional views taken on correspondingly numbered planes of Fig. 27;

Fig. 30 is a plan view, partly in section, of a portion of the power transmission mechanism for driving the rotors;

Fig. 31 is a sectional view taken along the plane 31-31 of Fig. 30;

Fig. 32 is a sectional view, taken along the plane 32-32 of Fig. 31;

Fig. 33 is a pictorial diagram showing one part of the aileron control;

Fig. 34 is a sectional view taken along plane 34-34 of Fig. 33;

Fig. 35 is a diagram similar to Fig. 33, of another part of the aileron control;

Fig. 36 is a pictorial diagram showing the mechanism for controlling the pitch of the rotors;

Figs. 37, 38 and 39 are detail sections taken along correspondingly numbered planes of Fig. 36;

Figs. 40 and 41 are diagrams illustrating the manner in which the rotor controls may be caused to effect the flight of the helicopter;

Fig. 42 is a diagram explaining the action of the aileron control; and

Fig. 43 is an enlarged detail section of the universal joint utilized in connection with the aileron control.

The general outlines of the helicopter are illustrated most clearly in Figs. 1 and 2. The fuselage may be made of any appropriate material; a plywood skin is indicated in the present instance. The fuselage terminates in a vertical tail 2 at the rear. In the grounded position of Fig. 1, the helicopter is shown generally as supported by the aid of landing gear incorporating wheels 3 and 4. Any appropriate landing gear, retractable or otherwise, may be used.

Accommodations for the pilot may include a seat 5 in the forward portion of the fuselage. The front of the fuselage 1 is equipped with windows, such as 6 and 7.

A pair of rotors 8 and 9 are arranged to provide the propelling forces for the helicopter. These rotors are arranged for rotation on substantially parallel axes 10 and 11. They are appropriately supported upon the outrigger structures 12 and 13, shown as joined to the fuselage 1. These outriggers, as well as all other parts of the helicopter body, may be made as heretofore mentioned of appropriate light material such as a light metal alloy, or plywood.

If wheel type or float type alighting gear is provided, the arrangement may be such that in the grounded position the rotor discs incline downward at the front, thus providing a forward component of the rotor thrust force which may be utilized to propel the craft on land or water.

The relationship of the rotor axes with respect to the fuselage is such that when the helicopter

is in flight at normal cruising speed, the fuselage may be substantially level, and the rotor discs may be inclined downward at the front, so that a part of the rotor thrust may be utilized for propulsion. The automatic provision for maintaining this flight attitude has been heretofore explained in connection with the location of the center of gravity.

As shown most clearly in Fig. 2, the distance 10 between the rotor axes 10 and 11 is considerably less than the outside diameter of the rotors. If the left hand rotor 8 rotates in a counterclockwise direction as indicated by the arrow a and if the right hand rotor 9 rotates in a clockwise direction as indicated by the arrow b, by appropriate synchronization of the rotor operation, the blades of the rotors will pass each other without interference. The manner in which the synchronous drive is obtained will be described in detail hereinafter. Furthermore, as heretofore 20 stated, the rotation is such that the blades advance at the region of the rotor disc overlap, and will retreat at the outboard regions of the discs.

In the present instance there are three blades 25 for each of the rotors 8 and 9. While, as herein-after explained, the blade surfaces are streamlined to offer little resistance to air flow, yet each blade such as 15, has a helicoidal twist from root to tip, and all of the blades of a rotor cooperate when rotated to operate as an air screw. Furthermore, the arrangement is such that each 30 of the rotor blades such as 15, may be angularly adjusted so as to vary the angle of attack of the blade surfaces, thereby providing the effect of a 35 variable pitch for the air screw. By thus varying the effective pitch of the rotors, the lifting effect is correspondingly varied.

Although in the present instance a relatively 40 low rate of rotor rotation is provided, of the order of 480 revolutions per minute, the rotor blades 45 serve to lift the helicopter and to cause it to rise. The rate of rise may be effected by controlling the pitch of the blades. The specific mechanism whereby this can be effected will be described in detail hereinafter.

As heretofore stated, the rotors 8 and 9 rotate in opposite directions, and since the rotations are synchronous, the reaction torques opposed to the 50 torques of the rotors, are balanced, and there is accordingly no tendency for the helicopter to turn about an axis parallel to the axes 10 and 11.

Each of the blades such as 15, is also provided with an aileron 17 on the trailing edge near the tip of the blade. These ailerons are so arranged 55 that they may be elevated or depressed with respect to the trailing edge of the corresponding blade 15. By appropriate control of the aileron elevation, it is possible to cause the helicopter to roll, pitch or yaw, as desired by the pilot.

As will be hereinafter explained, the ailerons 60 such as 17 are controlled so that they move, during one revolution of a rotor, to a maximum deviation, where they present a maximum angle of attack, and then they recede to a position where the 65 angle of attack is a minimum. This is a cyclic movement, in which one cycle is completed for each revolution; and the control is such that the aileron reaches the maximum angle of attack when the blade is in a definite angular position in its motion around the axis 10 of the rotor 8.

If the ailerons are maintained in a neutral position without any cyclic deviation as the rotors rotate, the effect is indicated in the diagram of Fig. 40. Here the rotors 8 and 9 are diagrammatically 70 illustrated, having their respective axes 10 and

11. The effective rotor action is then along the axes 14 and 11; that is, the forces produced by the individual blades can be combined into a single force operating along the axis of the corresponding rotor. The torque arms *c* and *d* of these forces about the axis 14 of the fuselage are equal; and since the forces are also equal, these forces provide torques that cancel out, and the helicopter is stable with respect to angular motion or roll, about the axis 14.

Let it now be assumed that when a blade on rotor 8 (Fig. 41) reaches a position corresponding to the radius 18, the aileron 17 associated therewith is depressed to a maximum degree from neutral, and as the blade departs from this position corresponding to the radius 18, the aileron is moved upwardly. Upon completion of another revolution, when the blade 15 again reaches the position of radius 18, the aileron has again moved to the maximum depressed position. In other words, the aileron is given a cyclic movement, reaching its maximum downward deviation from neutral at any angular position with respect to axis 10, such as the angular position represented by the radius 18. In a position diametrically opposite, represented by radius 241, the aileron may be elevated above the neutral position.

All of the ailerons on both of the rotors 8 and 9 are so simultaneously controlled that their maximum deviation positions fall along parallel radii. For example, if the ailerons on all of the blades of rotor 8 assume a maximum downward deviation along the radius 18, then the ailerons on all of the blades of rotor 9 assume a corresponding maximum deviation position along the radius 19, parallel with radius 18.

Such a cyclic operation of the ailerons causes the effective rotor lift action to occur, not about the axes 10 and 11, but about lines 20 and 21 displaced along the radii 18 and 19 from the corresponding axes 10 and 11. This shifting of the location of rotor action affects the flight of the helicopter. When the shift is along the radii 18 and 19, the center of rotor action of rotor 8 represented by point 20, is farther from the axis 14, as represented by dimension *e*. Accordingly this rotor 8 has a greater torque about axis 14 than in the position of Fig. 40. Conversely, the effective center of action 21 of rotor 9 is closer to the axis 14, as represented by dimension *f*. Its torque is therefore less. Accordingly the helicopter is urged in a direction such that the side upon which the rotor 8 is supported tends to rise and the side which supports the rotor 9 tends to lower. The plane thus rolls on axis 14. Since the rotor action has been also shifted further rearwardly with respect to the center of gravity 22, the nose of the helicopter is urged downwardly. The resultant combined effect is to cause the helicopter to turn and spiral downwardly in a counterclockwise direction as viewed in Fig. 41.

Similarly, if the ailerons have a maximum downward deviation from neutral in any other position of the blades, in the course of the revolution of the rotors, the reaction of the helicopter to such a control would be similar in general to what has been described. For example, in order to lower the helicopter without turning, the radii of maximum aileron action are made to extend toward the rear of the helicopter and normal to the line joining the axes 10 and 11. If it is desired merely to point the nose upwardly, the radii of maximum aileron action are made to extend toward the front of the helicopter (downward as viewed in Fig. 41) and normal to the line joining

the axes 10 and 11. For any other position of the radii 18 and 19, a corresponding tipping of the helicopter and a tipping of the nose either upwardly or downwardly is effected.

5 The center of gravity 22 is placed forward of the plane passing through axes 10, 11, by an amount approximating 10 percent. of the rotor disc diameter. Accordingly, stability of the airplane in flight is attained, and the axis 14 remains in an approximately horizontal position.

6 Directional stability of the helicopter in flight when subjected to side gusts is attained by virtue of the rotor arrangement. The action of the craft under these conditions may best be understood by referring to Fig. 2. Assuming that a side gust comes from the right hand side, its first effect will be to increase the lift on rotor 9 due to the momentary increased relatively velocity between the air and the blades in that region. 15 The increase in lift at rotor 8 will be relatively less, since the gust will have acquired some downward velocity by the time it reaches the region affected by rotor 8. The increased lift at rotor 9 results in an increased torque reaction 20 from rotor 9 which tends to yaw the helicopter in a counterclockwise direction, opposite to the direction of rotation of rotor 9. However, another effect of the gust is to react against the vertical stabilizer 2 in a direction to yaw the 25 helicopter in a clockwise direction. By using a correct combination of vertical stabilizer area and stabilizer moment arm from the center of gravity, the turning effect of the side gust may be entirely nullified, so that the net result after the 30 gust has subsided will be that the craft has been 35 inclined slightly from an even keel. This condition may be readily corrected by a simple movement of the control lever, as will be further explained herein.

Rotor mounting and supports

The manner in which each of the rotors 8 and 9 is rotatably supported at the extremities of the outriggers 12 and 13 may be best explained 45 in connection with Figs. 3, 4, 5, 6, 8, 9, 10, 27 and 28.

Fig. 3, which is an enlarged section through the axis 10 of the rotor 8 shows the upper extremity of the outrigger structure 12. The contour of this outrigger is shown to best advantage in Figs. 28 and 29. The outrigger has a streamlined form, hollow to accommodate a transmission mechanism (which will be hereinafter described) for rotating the rotors. At the end of 50 the outrigger, a hollow standard 23 is provided, made in this instance of wood. This standard 23 houses some of the important parts of the control mechanism, whereby the pitch control and the aileron control may be affected. In order to gain access into the standard 23, fore and aft removable covers 24 and 25 are provided.

A rotor hub 26 (Figs. 3, 8, 9 and 27) is shown 55 as made of wood, and as being built up of three equiangularly displaced portions forming recesses 27, 28 and 29 (Fig. 9). These recesses are of general rectangular configuration, and accommodate the correspondingly shaped inner ends of the spars 30, 31 and 32. These inner ends interfit, as shown most clearly in Figs. 3 and 9, to define a bore 40, coaxial with the rotor axis 10; they also define the enlarged recess 41 above the bore 40. The plane of contact 500 at the inner ends of these spars are clearly shown 70 in Fig. 9. The hub portions, filling in the spaces

at the roots of the spars, are made generally with smooth surfaces.

Upon spars 30, 31 and 32 are supported the blades 15 in a manner to be hereinafter described. The spar proper is of general circular form, the inner end of the circular portion substantially coinciding with a shoulder 34 formed on the hub 26 (Fig. 9). The axis of the spar, as shown by the line 35 in Fig. 3, is slightly above the horizontal, the axis of the blades therefore being slightly displaced from the normal to the axis of the rotor.

The blade 15, typical of all of the blades, may be built up of appropriate thin plywood as indicated most clearly in Figs. 9 and 10. The interior of the blade is made hollow for the accommodation of the spar 30. This may be accomplished by the aid of the interior walls 36 and 37 (shown also in Figs. 13, 14, 15 and 20). These walls extend longitudinally of the blade. The blade 15 may be further stiffened as by the aid of struts indicated generally by the reference character 38 in Figs. 9 and 10, which extend between the walls 36, 37 and the outer shell. Additional reenforcing corner pieces, brackets and walls are indicated in the drawings. These are designed as required, to provide the requisite strength, with lightness, for the entire blade structure.

The left hand end of the blade as viewed in Figs. 3 and 9, is provided with an enlarged shoulder 39, as by the aid of additional layers of plywood. This shoulder abuts against the corresponding shoulder 34 of the hub 26.

The opening 40, formed by the inner ends of the spars, extends coaxially of the rotor. Within this opening is a metal tubular shaft 42, which forms a drive shaft for the rotor. In order to attach the hub 26 to the tube 42, use is made of a flange 43 joined as by welding to the exterior of the tube 42. The welded-on metal is indicated by reference characters 44. Several fastening bolts 45 pass through the flange 43 and the hub 26, as well as through the metal upper ring 46. This upper ring 46 (Fig. 3) is provided with a vertical flange 47 extending into the recess 41. In order to maintain the hub contour smooth, a sheet metal cap or cover 48 is provided for the recess 41. It may be held appropriately in place by the aid of one or more fastening screws 49 threaded into the ring 46. The upper surface of this cover 48 forms a smooth continuation of the hub surfaces.

The tube 42 is rotatably supported by the aid of appropriate bearings adjacent its upper and lower ends. Thus for example, at the upper end, a series of balls 50 (Fig. 3) is accommodated between an outer race 51 and an inner race 52. The inner race 52 is urged against a narrow shoulder formed on the tube 42, as by the aid of the ring nut 53 threaded over a threaded portion of the tube 42. The lower end of the ring nut may be castellated to facilitate its tightening. Similarly the outer race 51 is held against a shoulder formed in a metal bearing standard 54 by the aid of the externally threaded ring 55. This ring 55 is threaded into the depending flange 56 of the bearing standard 54. This bearing standard is furthermore securely attached to the top of the hollow standard 23 as by the aid of a plurality of bolts 51.

Adjacent the lower end of the tube 42, balls 58 are provided. The outer race 59 for these balls is shown as supported in a metal bearing support 60. This bearing support 60 is provided

with a flange through which attaching bolts 61 pass for securely holding the member 60 to a supporting wall 62. This supporting wall 62 extends transversely across the bottom of the standard 23. The inner race 63 is shown as cooperating with an adapter 64, which is disposed between the inner race and the tube 42. The inner race and the adapter 64 are urged upwardly against a narrow shoulder on the tube 42 by the hub 65 of a driving disk 66. The upper ball bearing structure 50-51-52 may be a combination radial and thrust bearing.

The manner in which driving disk 66 is rotated will be described in connection with the description of the means whereby power is supplied to the rotors. Disk 66 may be a webbed casting. The disk 66 is splined to tube 42, as indicated at 501. The hub 65 of the disk is provided with a tapering counterbore 67 into which a wedge 68 may be urged as by the castellated ring nut 69, to hold the hub 65 securely in place.

The rotor 8 has now been generally described. A similar supporting structure is provided for the rotor 9, located on the right hand side of the airplane and at the tip of the outrigger 13.

Variable pitch mechanism for the rotor blades

The manner in which the rotor blades such as blade 15 may be adjusted about the axis of its corresponding spar 30, for adjusting the rotor pitch, will now be described. In this connection attention is especially directed to Figs. 9 to 20 inclusive. In these figures the manner in which the rotor blade 15 is mounted and controlled will be described; and it is to be understood that this description applies equally to all of the blades mounted on the rotors 8 and 9.

The sections of the blade 15 represented by Figs. 11, 12, 13, 14 and 15, illustrate the streamlining of the blade. Fig. 11, which is the section closest to the root, is shown in a position where its advancing edge 16 is slightly above the horizontal; this corresponds to substantially minimum pitch, substantially intermediate between a positive and a negative pitch. The leading edge 16 is slightly depressed at the tip of the blade as compared with its position adjacent the root.

Furthermore, as clearly shown in Fig. 8, the blade sections widen out as the tip is approached, until a maximum width is reached; and then the width of the blade is reduced quite rapidly to the tip. All this is well understood in rotor blade design. It is in this narrowing tip portion of the blade that the aileron 17 is provided at the trailing edge.

The blade 15, telescoping over the spar 30, is joined to the spar by the aid of spring metal hinges. These spring hinges are shown in Figs. 18 and 19. The spring hinge 10 (Fig. 18) is shown in assembled position in Figs. 13, 14, 16, 17 and 20. At its left hand edge, as viewed in Figs. 13, 14 and 20 it is provided with the upright body portion 71. At the top edge of the portion 71 there is a flange or web 72 that serves to strengthen this body portion. This flange or web 72 is broken away in places where it would interfere with other elements of the mechanism.

The body portion 71 is shown as abutting the partition 36 formed inside of the blade 15.

Projecting inwardly toward the spar 30, the body 70 carries a series of spring fingers 73. These extend obliquely to the axis of the spar 30 and their extremities are wrapped partially around the lower portion of the spar 30 (Fig. 20).

In this figure appropriate fastening means such as screws 74 are indicated for attaching the extremities of these fingers 73 to the spar 30. Furthermore, the spring hinge 70 is fastened to the interior of the blade 15 as by the aid of a number of anchoring nuts 75 (Figs. 16, 17 and 20). For the sake of clarity, the spar 30 is omitted from Figs. 16 and 17, it being understood that the spring fingers 73 actually extend below the spar, not shown.

The spring fingers 73 operate as ties between the spar and the blade, preventing movement of the blade 15 radially with respect to the axis of the rotor. These fingers restrict the motion of the blade 15 to one that has no component in a direction corresponding to the axis of spar 30. The resilience of the spring fingers 73 urges the advancing edge 16 downwardly, as viewed in Fig. 20. This is due to the force urging the fingers 73 to unwind with respect to the spar 30, that is restrained against rotation.

This tendency to unwind is, however, opposed by an opposite spring hinge 76, shown in detail in Fig. 19. It is shown in assembled relation with respect to the spar 30 in Figs. 13, 17 and 20. In this case also, a series of oblique spring fingers 77 is arranged to be wrapped around the lower side of the spar 30 and to be attached thereto as by the screws 78. The spring hinge 76 is quite similar in structure to the spring hinge 18, the fingers 77 extending in the same general oblique direction, that is, from the outer edge of the hinge 76 inwardly toward the root of the rotor blade. This is most clearly indicated in Fig. 17. Similarly, the upright wall 79 of the spring hinge 76 is shown as abutting the partition 31 formed inside of the blade 15.

The ends of the spring fingers 77, as shown most clearly in Fig. 17, overlap the bases of the spring fingers 73. Similarly, the ends of spring fingers 73 overlap the bases of the spring fingers 77. This interlaced arrangement does not result in any interference between the fingers, for the ends of all of the fingers are located on the periphery of the spar 30; and the bases of the fingers are considerably below that periphery (Fig. 20).

The spring hinges 70 and 76, in their tendency to unwind with respect to spar 30, act in opposition to each other (Fig. 20). Accordingly with all controls in neutral, the arrangement can be such, as heretofore stated, that the advancing edge 16 at the blade root is disposed slightly above the plane 503 (Fig. 11) that corresponds to the axis of symmetry of spar 30; and as the tip is approached, this edge is lowered. In other words, there is a slight washout. But even at the tip of the blade, edge 16 is still slightly above the plane 503.

As is evident from the sections, Figs. 11, 12, 13, 14 and 15, the diameter of the spar 30 is reduced as the tip of the blade 15 is approached. The spar is shown as built up of several wooden segments leaving a hollow free rectangular space 80 in the interior of the spar (see also Fig. 3). Furthermore, as shown most clearly in Fig. 10, the spar end 81 is closely adjacent a partition or wall disposed across the interior of the blade 15. This spar end 81 is shown as reduced in a section and may be provided with a thin metal ferrule 85 (Fig. 15).

Cooperating with this end 81 of the spar 30 is a stop yoke 83. This stop yoke extends over the top of the spar end 81. The ends of the yoke 83 are provided with tapped apertures for the accommodation of the adjusting bolts 84. These

bolts 84 pass through the wood blocks 85 disposed adjacent the partitions 36 and 37.

The yoke 83 serves to prevent the inner contour of the upper skin of the blade from coming in frictional contact with the upper surface of the spar 30. By appropriate adjustment of the bolts 84, the blade 15 can be maintained at the desired position with respect to the spar 30.

Fig. 20 illustrates the angular adjustment of the blade 15 by operation of the hinges 70, 76. In the position corresponding to the full lines, the pitch is at a neutral value, corresponding to a small positive pitch. The maximum pitch is represented by the position of the center line 87, the advancing edge 16 having been moved upwardly by about $7\frac{1}{2}$ ° from the zero pitch position. In this process the hinge 70 has rolled farther up on the spar 30 to attain the position corresponding to the center line 87; and similarly the hinge 76 has been unwound from the spar 30. This process therefore causes the blade 15 to move slightly toward the right, due to the winding up process with respect to the hinge 70. Similarly, for producing a negative pitch corresponding to the center line position 88, the leading edge 16 has moved toward the left as viewed in Fig. 20. This corresponds to an unwinding of the hinge 70 from the spar 30 and a corresponding winding up of the hinge 76 on the spar 30.

The maximum negative pitch may be made the same as the maximum positive pitch by providing approximately a $7\frac{1}{2}$ ° displacement of axis 88 with respect to the axis 89, that corresponds to a neutral pitch.

Rocking of the blade 15 with respect to the spar 30 is accomplished by the aid of bellcrank mechanisms illustrated most clearly in Figs. 9, 10, 12, 13, 14, 16 and 17. These mechanisms operate upon the blade to move it with respect to spar 30.

A series of bell cranks are pivotally supported along the spar 30. In the present instance, six such bell cranks are indicated in Figs. 9 and 10 and are marked with the reference characters 90, 91, 92, 93, 94 and 95. Some of these bell cranks are also illustrated in Figs. 13, 16 and 17.

One of the intermediate bell cranks 92 is illustrated in Fig. 13 as well as in Fig. 16. Since it is typical in structure and representative of all of the bell cranks 90 to 95 inclusive, its description can serve as a general description of all of them. All of the bell cranks are operated in unison on axes that are arranged transverse to the axis of the spar 30.

For pivotally supporting the bell crank 92 upon the spar 30, use is made of a bracket 96, shown to best advantage in Fig. 13. This bracket is provided with an arcuate base 97, in close contact with the outside periphery of the spar 30 and fastened thereto by any appropriate fastening means.

The bracket 96 supports a stationary pivot pin 98 (see also Fig. 16) which forms a stub shaft for pivotally supporting the crank 92. Appropriate cotter pins may be utilized with washers to ensure against axial displacement of the crank 92 with respect to shaft 98. While the upright arm of the crank 92 is shown as made of thin sheet metal, the other arm 99 is shown as formed of a relatively thick material slotted to receive the sheet metal out of which the arm 92 is made. The parts are held together by appropriate fastening means, such as rivets 100.

The arm 99 ends in a ball 101 (Figs. 14 and 16). This ball 101 is accommodated in a cylindrical

aperture in a hub 102 formed on the bracket 103. This bracket is fastened to the blade 15 as by the aid of several fastening devices. Some of these fastening devices are formed by the rivets 104 which pass through the hinge 70; another of the fastening devices is the flat headed bolt 105 passing through a corner piece 106 and through a flange 107 formed on bracket 103.

Now if it be assumed that the crank 92 is rotated about the pivot pin 98 in a counterclockwise direction as viewed in Fig. 16, the ball end 101 will depress the bracket 103 and will cause rotation of the blade 15 in a corresponding counterclockwise direction as viewed in Fig. 14, causing a lowering of the leading edge 16. A clockwise rotation of crank 92 causes a corresponding clockwise rotation of the blade 15, and a consequent raising of the leading edge 16. By providing the ball connection 101, any variation in the angular position of the bellcrank 92 about its pivot pin 98 will not cause any binding within the hub 102.

Bell crank 90 (Fig. 16) is of generally the same structure as bell crank 92, although its upright arm is somewhat longer. Its ball end 535 operates within a cylindrical aperture in the boss 536 of bracket 537. This bracket 537 is fastened to the inside of the blade 15, in a manner similar to that illustrated for bracket 103 in Fig. 14.

Similarly, the bell crank 91 cooperates with a bracket 108 similarly fastened to the inside of the blade 15. All of the other bell cranks 93, 94 and 95 indicated in Fig. 10 similarly cooperate with the brackets carried by the blade.

Link connections are formed between all of the bell cranks so that they are operated in unison for imparting a definite angular movement to the blade. However, since the diameter of the spar 30 gradually tapers toward the tip of the blade, smaller bell crank parts are required; and therefore a linkage system is provided that can be accommodated in the restricted spaces.

The first element of the link mechanism is formed by a lever 109 shown at the left hand portion of Fig. 16 and also indicated in Fig. 12. At its lower end this lever 109 is pivotally supported upon a pivot pin 110 carried by the bracket 111 attached to spar 30. This bracket 111 has generally the same structure as bracket 96 described in connection with the supports for the bell cranks. At the upper end of lever 109 a link structure 112 is provided, connecting the lever 109 with the upright arm of the bell crank 90. This link structure 112 may be in the form of a pair of thin sheet metal straps between which the lever 109 and the upright arm of crank 90 are disposed. The link structure is pivoted at its ends to the end of lever 109 and of the upright arm of crank 90.

Operation of the lever 109 is provided in this instance by a cable 113. The manner in which this cable is guided and operated will be described hereinafter. For the present it is sufficient to note that at its right hand end as viewed in Fig. 16 it is provided with a loop 114. This loop passes over a grooved roller 115 accommodated between the sides of a link structure 116. This link structure 116 is formed of a pair of thin sheet metal straps. The right hand end of the link structure 116 is pivoted, as by the aid of a pivot pin 117, to an intermediate point of the lever 109.

Pull of the cable 113 toward the left thus causes

consequent rotation of the lever 109 and crank 90 in a counterclockwise direction.

Angular motion of crank 90 is transmitted to cranks 91 and 92 by the aid of a link structure 118. This link structure (Figs. 13 and 16) is pivoted at its left hand end as by the aid of the pivot pin 119, to an intermediate point of the upright arm of crank 90. This link structure 118 is likewise formed of a pair of thin sheet metal straps disposed on opposite sides of the upright arm of the crank 90.

The right hand end of the link structure 118 is pivoted as by the aid of the pin 120 to the extremity of the bell crank lever 92. It is also pivotally connected to the extremity of the bell crank lever 91 at an intermediate portion of the length of the link structure, as by the aid of the pivot pin 121.

Although the link structure 112 is joined to the bell crank 90 at a greater distance from the axis of rotation of the bell crank 90 than the link structure 118, by appropriate design of the bell crank dimensions, the effective motion of all of them upon the blade 15 can be made equal.

The operation of the bell cranks 93, 94 and 95 illustrated in Fig. 10 is accomplished by the aid of a link structure 122, similar to link structure 118. It is pivoted as by the aid of a pivot pin 123 (Fig. 16) to the crank 92, and at its extremity to the bell crank 95. The intermediate bell crank levers 93 and 94 are pivotally joined to intermediate portions of this link structure 122. Here again the proportions of the bell cranks 93, 94 and 95 are consistent with the requirements of the blade movements. By use of the succession of link structure 112, 118 and 122 arranged in a manner illustrated, it is possible to accommodate the lever mechanisms for varying the position of the blade 15 in the confined spaces between the spar 30 and the interior of the blade structure.

A pull on the cable 113 as viewed in Fig. 16 toward the left obviously causes rotation of all of the cranks in unison in a counterclockwise direction. This counterclockwise direction of rotation depresses all of the ball ends such as 101 of the bell cranks, causing the angle of attack of the blade to be reduced, the leading edge 16 being lowered as viewed in Fig. 20. The cable 113, however, is incapable of providing a thrust to rotate the bell cranks in a clockwise direction, for increasing the angle of attack, corresponding to a raising of the leading edge 16. In order to provide a force against which the pull of the cable 113 can be exerted, and which serves to rock the cranks in a clockwise direction when tension of the cable 113 is released, several forces are utilized.

One of these forces is that created by the rotation of the rotor structure about its axis 10 (Fig. 2). Such a rotation creates a centrifugal force upon the crank mechanisms, urging them in a clockwise direction. These cranks and links are purposely made heavier than would otherwise be required, so as to increase the centrifugal forces, which are functions of the mass. When the rotor rotates, therefore, the pull on the cable 113 is opposed by these centrifugal forces.

However, in order to make it possible to test the controls even when the rotor is not rotated, a supplemental spring may be utilized to urge all of the bell cranks in a clockwise direction. Such a force is produced by the aid of a long tension spring 124 (Figs. 9, 16 and 14). The left hand end of this tension spring is anchored by

the aid of a hook 125 to a pin 126 extending transversely of the link structure 118. This hook 125 extends between the two strips forming the structure 118. The right hand end of the spring 124 is anchored on a web of the bracket 103.

Still another force operating in opposition to the pull of the cable 113 is that produced by the air load operating on the blade structure. This air load is effective, however, only when the rotor is in operation. The direction of the resultant force due to the air load is upward and to the left of the axis of the spar 30 as viewed in Fig. 20. This position of the resultant force due to the air load is due to the specific design of the blade structure. This resultant force is caused to be quite close to the axis of the spar 30, and therefore offers relatively little opposition to the pull of the cable 113.

The manner in which cable 113 may be pulled to control the pitch of the rotor blade 15 may now be described in connection with Figs. 3, 4, 6, 9 and 16.

The cable 113 is guided downwardly into the drive tube 42. The guide for this purpose is shown in the form of a tubular member 127 (Fig. 3). The upper extremity of the tube 127 carries an end 505 that is held in place by a clip 128. This clip is attached to the spar 30 and adjacent the root end thereof. Thence the guide tube 127 extends through an appropriate groove in the spar 30 and describes an arc for directing the cable 113 into the drive tube 42. The lower end of the guide tube 127 is fastened into an end 129 attached as by the aid of a screw 130 to the wall of the tube 42. The ends 128, 505, may be threaded over the ends of the tube 127.

The other blades of rotor 8 are similarly controlled and constructed, and they are similarly provided with control cables 131 and 137 and guide tubes 132 therefor (Figs. 3 and 6). All three of the guide tubes 127, 132 extend into the hollow space 41 before they curve downwardly into the tube 42.

The cable 113 after passing through the guide tube 127 is joined to a terminal member 133 (Fig. 3) which has a threaded extension 134. This threaded extension passes through an anchor plate 135 (Figs. 3 and 4). This plate 135 is shown as having a large central aperture 136 and is of general triangular configuration, the outer edge being in sliding contact with the interior surface of the drive tube 42.

The other cables 131 and 137 are similarly equipped for controlling the other two blades of the rotor 8.

Each of the threaded extensions, such as 134, is held in adjusted position with respect to the plate 135, as by the aid of a nut 138.

The plate 135 is guided for axial movement in tube 42 so that a downward force exerted upon the plate 135 will exert a uniform pull on all of the three cables 113, 131 and 137. Confinement of the movement to axial direction is provided by the aid of the three screws 139 (Figs. 3 and 4) that are threaded radially into the plate 135. Each of these screws are provided with a cylindrical shoulder 140 that extends through and is guided by a corresponding vertical slot 141 formed in the tube 42. Spring washers 506 (Fig. 4) may be provided below the heads of the screws 139.

The screws 139 also pass through a ring 142 that has a sliding fit with relation to the exterior of the tube 42. Provisions are made for moving this ring 142 in an axial direction, and

thereby to adjust the position of the plate 135. The ring 142 rotates with the tube 42, since it is placed in driving relation thereto by the screws 139.

5 Axial adjustment of the position of the ring 142 is accomplished through a thrust bearing. Thus the lower end of the ring 142 carries a inner ball race 143. This race has a sloping surface upon which are accommodated a series of balls 144. The outer race, which is non-rotary, is formed in a ring 145. This ring has an upright flange 146 in sliding contact with the ring 142. It is also provided with a flat shoulder 147 (see also Fig. 6) against which a lowering force can be exerted to urge the race 143 downwardly through a thrust exerted through the balls 144.

A thrust thus exerted in a downward direction will cause the cables 113, 131 and 137 to be placed in tension. As this downwardly directed force is released, the various forces heretofore described, acting in opposition to the cable pull, will cause movement of the plate 135 upwardly.

For exerting the downward force upon the shoulder 147, use is made of a yoke structure 148 (Figs. 3, 4 and 6). This yoke structure may be formed conveniently of a hollow tubular member, of general U-shape configuration, embracing tube 42. In order to lend rigidity to the structure, a cross brace 149 (Fig. 4) may extend across the legs of the U.

20 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

25 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

30 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

35 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

40 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

45 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

50 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

55 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

60 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

65 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

70 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

75 The extremities of the legs are flattened and form ears 150. These ears may be pivoted upon pivot pins 151 supported in the standards 152. These standards 152 are conveniently bolted to a wood block 153 fastened to the transverse partition 62 by any appropriate means.

The left hand end of the hollow shaft 160 may be further appropriately supported by the aid of the bearing sleeve 163 (Fig. 4) that passes through the plywood wall 164. This plywood wall 164 as shown most clearly in Fig. 3, forms a continuation of the hollow standard 23.

Exterior of the wall 164, the hollow shaft 160 is provided with a tapered portion 165 over which is disposed the hub 166 provided with a corre-

spondingly tapered aperture. If desired the hub 166 may be keyed to the tapering portion 165. The hub 166 is held in assembled relation with respect to the tapering portion 165 as by the aid of a screw 167 threaded into a plug fastened into the end of the shaft 165. This screw urges a washer 168 against the hub 166.

Hub 166 is formed integrally with a grooved sheave segment 170, about which a control cable 431 may pass. This control cable is shown to best advantage in Fig. 36, wherein it is seen that the sheave segment 170 is provided with an extension 171 to which the end of the control cable 431 may be attached. Thence the cable 431 passes around the segment 170 and is manipulated in a manner that will be described in connection with the apparatus under the control of the operator for controlling the flight of the helicopter. The sheave segment 170, with its associated parts, is concealed by the aid of the housing 24 (Figs. 27 and 28) that cooperates with the standard 23. This housing is in the form of a cover that may be removed for access to the apparatus. Similarly, the housing cover 25 shown in Figs. 3 and 28 serves as an extension for the hollow standard 23 to enclose some of the additional parts that will be described hereinafter.

A description of the manner in which the pitch of the rotors may be adjusted is now complete. A simultaneous pull on all of the three control cables 113, 131 and 137 equally affects all of the three blades of the rotor 8. A similar arrangement is provided for the control of the blades for rotor 9.

Aileron control mechanism

As heretofore stated, each of the blades 15 carries an aileron 17 adjacent the tip and on the rear or trailing edge of the blade. The mechanism for directly moving this aileron 17 can be best described in connection with Figs. 19 and 21 to 26 inclusive.

Aileron 17 is shown as made from wood and tapered toward the rear edge in conformity with the exterior surface of the blade 15. As shown most clearly in Figs. 15, 21, 23, 24, and 25, that portion of the trailing edge of the blade 15 which is adjacent the aileron 17 may be provided with a block 173 that may be built up of plywood or the like. Hinges are provided for the aileron 17 so that it may be swung to assume an elevated or lowered position, as indicated in dotted lines in Fig. 15. These hinges are illustrated generally in Fig. 10 by the reference characters 174 and 175. The hinge structure 175 is shown in greater detail in Figs. 21 and 25. Since the other hinge structure 174 is similar, a description of the hinge structure 175 is sufficient for both hinges.

By the aid of these hinge structures 174 and 175, it is possible to move the aileron up or down with respect to the blade 15 and thereby to reduce or increase the effective lift over the tip portion of the blade.

As shown most clearly in Fig. 25, a hinge pin 176 extends through a hinge member 177 that is carried at the rear edge of the blade 15. For this purpose hinge member 177 is shown as formed integrally with a flange 178. This flange 178 abuts the left hand face of the block 173. This block 173 is shown as re-enforced by another block 181 disposed back of the block 173. Through the blocks 173 and 181 extends the threaded shank 179 of the hinge member. The hinge member is held in place by the aid of the nut 180 threaded on the shank 179. If desired, washer 182 may be

interposed between the nut 180 and the block 179.

The cooperating hinge member carried by the aileron 17 includes a clevis 183 to which is integrally attached a shank 184. This clevis 183 abuts the bottom surface of a slot 185 in the edge of the aileron 17. An oval slot 186 is also provided transversely in the aileron to accommodate the fastening nut 187 and washer 188 that cooperates with the threaded shank 184.

The same general structure for the hinge is utilized in connection with the hinge 174 (Fig. 10).

Movement of the aileron 17 about the hinge pins 176 is accomplished by mechanism illustrated most clearly in Figs. 21, 22 and 26. Intermediate the two hinges 174 and 175 the forward edge of the aileron 17 is provided with a supplemental hinge structure including a hinge ear 189. This hinge ear is fastened to the aileron 17 so that its hinge axis is coincident with that of hinges 174, 175, by the aid of a shank 190 (Fig. 22), integrally formed with the hinge ear 189. An oval transverse slot 191 in the aileron is provided to permit the use of a fastening nut 192 for the shank 190. If desired, a washer 193 may be interposed between the nut 192 and the adjacent aileron surface.

The hinge ear 189 is disposed between the ears 194 of a hinge bracket 195 that is attached to the trailing edge of the blade 15. This bracket 195 is in the form of a generally rectangular block. As shown most clearly in Figs. 10, 22 and 23, this block carries upper and lower flanges 196 and 197. The lower flange 197 is also shown in dotted lines in Fig. 21. These flanges are utilized to attach bracket 195 to the trailing edge of the blade 15. Thus the outer surfaces 509 and 510 of these flanges form a smooth continuation of the blade surfaces, as indicated in Figs. 22 and 23. Slight convexities 511 (Figs. 10 and 23) are provided on these surfaces to allow the passage of apertures through the bracket 195, for a purpose hereinafter to be described. To accommodate bracket 195 (Fig. 21) the block 173 that is adjacent the edge of the blade 15, may be cut away. Accordingly the space between the two flanges 196 and 197 is open to the hollow interior of the blade 15.

The hinge ear 189 is rotatably mounted with respect to a pin 198 (Fig. 22) carried between ears 194 as by the aid of a ball bearing structure 199. The outer race of this ball bearing structure is fastened in an aperture in the ear 189; and the inner race is mounted directly upon the pin 198.

In the position of Fig. 22, the aileron 17 is neutral, its plane of symmetry 208 corresponding to the plane of symmetry of the blade 15. The aileron 17 may be depressed about the axis of pivot pin 198 to vary the position of the aileron 17 as occasion requires. Control of the position of the aileron around the axis of pin 198 is effected in this instance by rocking a lever 210 (Figs. 21, 22, 23 and 26) about an axis 211 that is normal to the plane of symmetry 208, or vertical as viewed in Fig. 22. This lever is located within blade 15. The conversion of a rotary movement about axis 211 to a rotary movement about the axis of pin 198 is accomplished in a novel manner now to be described.

The lever 210 has a hub portion 212 accommodated between the flanges 196 and 197 of the bracket 195. A pivot pin 213 (see also Fig. 10) extends through the hub and is fastened in the bracket 195, thereby providing a pivot for the rocking of the arm 210. Rotational movement of

the arm 210 about the axis 211 provides a thrust upon one or the other of the arms 206, 214, integrally joined to the hinge member 189. Thus for example upon clockwise movement of the arm 210 as viewed in Fig. 21, a thrust is made against the lower arm 214 for raising the aileron 17. A counterclockwise rocking of the arm 210 as viewed in Fig. 21 causes a thrust to be exerted upon the arm 206 thus lowering the aileron 17.

The thrust in these two directions is obtained by the aid of thrust rods 200 and 201. These thrust rods extend through large clearance apertures 202 formed in bracket 195. For this purpose each of the thrust rods 200 and 201 is provided at their ends with ball or spherical portions such as 203 and 204 (Fig. 26). The end 203 of rod 200 is accommodated in a spherical socket 205 disposed in the projection 206. The ball 204 is accommodated in a similar spherical socket 209 that is supported on the arm 210. The direction of the thrust imposed upon the arm 206 through the rod 200 is toward the right as viewed in Fig. 22 and also upward. In other words, while the center of the ball end 203 falls on a point within the socket 205 which is central of the hinge member 189, the center 207 of the other ball end 204 is spaced to the left of that center as shown most clearly in Fig. 21. The center 207 of the ball end 204 may be near the plane 208, which passes through the axis of the aileron hinge and corresponds to a plane of symmetry when the aileron is in neutral position (Fig. 22). Center 207 remains the same distance from this plane upon movement of arm 210, because axis 211 about which arm 210 is movable, is normal to plane 208. In this way as arm 210 is rocked, the center 207 of the ball 204 must always remain at a constant distance from the plane 208. During this rocking motion the axis of the push rod 200 varies its position; but an effective thrust is nevertheless exerted in a direction slanting inwardly as viewed in Fig. 22, and upwardly against the socket 205.

Socket 209 in this instance is shown as formed in the head 215 of an adjusting screw 216. This screw 216 is threadedly engaged in the boss 217 formed integrally with the arm 210. The axis of the boss has an inclination approximating that of the push rod 200 when the apparatus is in the neutral position shown. In order to bind the screw 216 in any adjusted position, a slot 218 may be provided in the boss 217 transverse to the axis of the screw 216, and near the right hand end thereof as viewed in Fig. 26. There is sufficient flexibility in this separate right hand portion to provide a locking action for the screw 216.

By appropriate adjustment of the screw 216 in the boss 217, any material play between the ball ends 203, 204 in the sockets 205 and 209 may be taken up.

There has now been described the manner in which a counterclockwise movement of the arm 210 as viewed in Fig. 21, is made effective to lower the aileron 17.

A similar effect, for raising the aileron 17, is produced when the arm 210 is rotated in a clockwise direction as viewed in Fig. 21. In this case it is the thrust rod 201 that urges the aileron 17 in an upward direction and thrust rod 200 follows the motion of the arm 210 and the screw 216. Arm 214, being joined to hinge ear 189, is moved in this process. It engages the end of the push rod 201, which is arranged similarly to rod 200. Its inner end terminates in a spherical portion, the center of which likewise moves in a plane

normal to the axis 211, and at the same distance from axis 208 as center 207. An adjusting screw 219 similar to adjusting screw 216 is provided for this inner ball end.

Due to the symmetry of the arrangement, a thrust exerted on rod 201 by counterclockwise movement of arm 210 results in a movement of the screw 219 that is just sufficient to ensure contact being maintained at both ends of the thrust rod 201 between the screw 219 and the arm 214.

By the provision of this mechanism, raising and lowering of the aileron 17 about its hinges is accomplished by direct thrust secured by the motion of the arm 210.

15 This arm 210, as shown most clearly in Fig. 22, extends into the hollow portion of the blade 15. To the free end thereof is attached a control sector 220. This control sector is disposed between the two ears 221 of the arm 210. It is fastened thereto as by the aid of the bolt 222. 20 Angular motion of the sector 220 about bolt 222 is prevented by the aid of a V-shaped notch 223 formed in the inner end of the control sector, and fitting over a corresponding projection 224 disposed at the bottom of the space formed between the two arms 221. Furthermore, a counterweight 225 is mounted upon the right hand portion of the sector 220. Inspection plates 538 disposed on opposite sides of blade 15 permit access to bolt 222.

25 Counterclockwise motion, to lower aileron 17, may be imparted to the arm 210 by the aid of a control cable 226, accommodated in a groove formed in sector 220. A guard block 545 is provided with an arcuate face 546 close to the sector. This control cable is also illustrated in Fig. 3 as passing through the central hollow space 80 in the spar 30. The cable 226 is also indicated in Figs. 11, 12, 13 and 14. As there shown the 30 cable has a position substantially coincident with the axis of the spar 30. Accordingly rotation of the blade 15 upon its spring hinges for varying the pitch of the rotor has no appreciable effect upon the position of the cable 226.

35 40 While the cable 226 may exert a pull to rotate the arm 210 in a counterclockwise direction and thereby to lower the aileron 17 it is incapable of exerting any thrust to move the arm 210 in the opposite direction. Accordingly some additional forces must be provided for keeping the cable 226 under tension at all times. The centrifugal force due to rotor rotation, operating upon weight 225 forms one component of this opposing force. As the rotor blade 15 rotates about the axis 10, 45 a centrifugal force is set up, imposing a force on weight 225 that is radial to the rotor axis.

50 In order to make it possible to test the aileron control even when the rotor 8 is not rotating, a spring force is provided operating in opposition to the pull of the cable 226; that is, to raise the aileron 17. In the present instance this spring force is obtained by the aid of torsion exerted by a flat spring structure 227 (Figs. 21, 23 and 24). This spring structure is located in an appropriate recess in the edge of aileron 17. The left hand end of this spring 227 is joined as by rivets 228 to ears 229. These ears 229 are formed integrally with the head 230 formed on the aileron hinge pin 198. This head 230 is of general circular configuration, but as seen in Fig. 23, its right hand end is flattened to cooperate with the flattened surface 231 formed on the hinge bracket 195. Accordingly the pin 198 is restrained against rotation. The pin is threaded 55 at its left hand extremity for the accommodation

of the nut 232 for maintaining the pivot pin against axial movement.

The spring 227 is twisted so that it becomes substantially vertical where it passes around the curved bottom of a slot 233 disposed in a pin 234. This pin 234 passes transversely through the wide edge of the aileron 17 as shown most clearly in Fig. 24 and is firmly held therein by the force exerted thereon by the spring 227. The slot 233 aligns with a slot 235 disposed in the wide edge of the aileron to permit the passage of the spring 227 into the slot 233. The right hand end of the spring 227 is formed with an enlarged threaded extension 236 (Fig. 21). This extension passes through an appropriate aperture 237 in the aileron and is provided with a nut 238 for applying a tension to the spring 227. To provide a space for the nut 238, a slot 239 may be provided transversely in the aileron 17.

As is apparent from a consideration of Fig. 21, the left hand end of the spring 227 is fixed relative to the blade 15; and accordingly the torsion on the spring 227 is such as to urge the aileron 17 upwardly as viewed in Fig. 23. Accordingly this spring force operates in opposition to any pull on cable 226.

At appropriate places on the body of the aileron 17, reinforced portions such as 240 (Fig. 21) are provided properly to accommodate various hinge structures, as well as the spring 236. In order to ensure, however, adequate streamlining, the slots such as 183, 191, and 239 may be filled in with plastic wood or the like after the aileron structure is fully assembled.

As heretofore explained in connection with the diagram of Fig. 41, the ailerons 17 on each rotor are arranged to be controlled so as to provide any desired deflection within the requirements for control of the helicopter's flight, and to be controlled in such a way that the desired maximum deflection may be made to occur cyclically at any desired phase position of the corresponding blades. Thus radial line 18 of Fig. 41 illustrates the position of the blade when the aileron 17 is in its maximum downwardly deflected position. As the blades arrive in succession at the position illustrated by line 18, their ailerons likewise assume the maximum downwardly deflected position. Conversely in the position illustrated by the radial line 241 which is 180° displaced from line 18, the aileron on each of the blades as it passes that position, has reached its maximum upwardly deflected position. As the blade moves in a counterclockwise direction between the position of line 241 to the position of the line 18, the aileron is angularly moved, analogously to a simple harmonic motion, to assume the maximum downwardly directed deflection, when the blade reaches the position corresponding to line 18.

In order to accomplish the type of aileron motion just described, control arm 210 is actuated to and fro harmonically through one complete cycle in each revolution of the rotor about the axis 10.

The manner in which this harmonic motion of the control arm 210 is effected in correspondence with the rotation of the rotor may be described particularly with reference to Figs. 3, 4, 5, 6, 7, 9, 42 and 43.

The inner end of the cable 226 attached to the aileron control of the blade 15 extends generally radially of the axis 10 (Fig. 3) of rotation of the corresponding rotor. One other cable 242 corresponding to another blade of the rotor is illus-

trated in Fig. 3. The inner ends of these cables are accommodated within the recess 41 above the drive tube 42. These inner ends are all joined to an anchor 243. This anchor is made in the form of a spherical socket with radial lugs 245. The spherical socket embraces ball 244 to form a ball and socket joint. End clevises 246 joined to the cables 226, 242, and 248 attach to lugs 245 by means of pivot bolts 247.

10 Although only two cables 226 and 242 are illustrated in Fig. 3, the third cable 248 is shown in Fig. 9, for the third rotor blade.

So long as the ball 243 remains in the neutral position of Fig. 3, that is, with its center falling on the axis 10, rotation of the rotor does not affect the aileron at all. However, if the ball 244 is moved off the axis 10, as indicated in Fig. 43,

15 harmonic motions of the ailerons 17 will be produced. Furthermore, the angular position of the line joining the center of the ball 244 with the axis 10, determines the angular position of the blades at which the ailerons will attain their maximum downward deflection. The diagram of Fig. 42 explains this action. This diagram is a top plan view of the cables that are joined to the control sectors 210 (Fig. 21) for each of the blades.

20 Now let us assume that the ball 244 be moved say to the position shown in broken lines, that is, downwardly as viewed in Fig. 42 and slightly to the left. The line 250 joining the axis 10 with the center of the ball 244 in the full line position, represents the extent to which the cable 226 or 242 or 248 is pulled inwardly of the axis 10 when the blades in succession reach the position illustrated by the dot-and-dash line 249. Accordingly, the angular position of radius 249 corresponds to the position of the blade where the harmonic motion of the aileron on the blade reaches its maximum.

30 Once ball 244 has been adjusted, all of the cables 226, 242 and 248 are similarly affected, and all of them have a maximum inward pull when the radial line 249 is reached by the corresponding blade.

35 The angular position of line 249 can obviously be adjusted by a corresponding adjustment of the angular position of the line 250 which joins the center of the ball 244 and the axis 10. For example, if the center of the ball 244 moves downward as viewed in Fig. 42, all corresponding to a forward movement of the ball with respect to the longitudinal axis of the plane, the maximum deflection of the aileron occurs along a vertical line as viewed in Fig. 42. This is the equivalent 40 of the shifting, toward the rear, of the resultant of the rotor action, all as has been explained in connection with Fig. 41. Likewise, a shifting of the ball 244 to the left or right as viewed in Fig. 42 will cause a corresponding shift of the rotor action to the right and to the left respectively.

45 The centrifugal forces operating on the three counterweights 225 (Fig. 21) as the three cables 226, 242, and 248 are tensioned and relaxed in the manner illustrated in Fig. 42, are such that 50 they have a stabilizing effect, tending to move the ball 244 to the neutral position.

55 In the neutral position illustrated in Figs. 21 and 22, rotation of the rotor about its axis 10 sets up a centrifugal force due to weight 225 which 60 creates a clockwise turning movement about pivot 211 of the arm 210. Now, in the event cable 226 moves radially outwardly, the other two cables move radially inwardly. The outward movement of cable 226 causes the weight 225 to move closer 65 to the pivot 211 of arm 210. Thereby the torque 70

75 to the pivot 211 of arm 210.

tending to turn the arm 210 in a clockwise direction is considerably reduced. This is obvious, since the torque about pivot 211 is measured by the product of the centrifugal force acting on weight 225 and the length of the normal from axis 211 to the direction of that centrifugal force. The length of this normal is reduced as the weight 225 moves in a clockwise direction, as viewed in Fig. 21.

On the other hand, should cable 226 move inwardly, the length of the normal is not materially increased; and, therefore, the torque urging the arm 210 in a clockwise direction is not materially increased. This is obvious, since the angular position of the weight 225 with respect to the axis 211 is such that it is nearly normal to the direction of the centrifugal force. Accordingly, when the system is urged out of the neutral position, as indicated in the dotted lines in Fig. 42, the weights cooperating with those cables that have been pulled inwardly exert a centrifugal force that can overpower the centrifugal force exerted by the weight cooperating with the cable that has moved outwardly. By this means, the combination of three arms and counterweights mutually joined by cables as shown in Figs. 9, 10, 21 and 42 is made to behave as a stable rotating system, since any displacement from the neutral position sets up forces which tend to return the system to its neutral position.

The mechanism for controlling the position of the ball 244 is illustrated most clearly in Figs. 3, 4, 5, 6, 7 and 43.

The ball 244 is shown as mounted on top of a mast 251 (Figs. 3 and 6). This mast is shown as slightly tapering and in the neutral position illustrated in Fig. 3, its axis coincides with the axis 10 of the rotor. The axis of the mast 251 may be adjusted universally about the point 252 (Figs. 3, 6 and 43) which falls upon the axis 10 of the rotor. Any appropriate universal joint to effect this result may be used. The radius from the point 252 to the center of the ball 244 is quite large; in this way even a slight angular displacement is sufficient to cause a considerable linear displacement of the ball 244 from the axis 10. The effect of the angularity of the mast upon the height of the ball 244 may therefore be ignored.

The provision of a universal joint capable of universal adjustment about the point 252 is conveniently accomplished by aid of supporting elements mounted in the interior of the tube 42. By appropriate restraints hereinafter to be described, while mast 251 rotates about its own axis, the mast axis is adjustable to a definite, fixed position, and does not describe a conical motion with point 252 as the apex of the cone.

The universal supports for the mast 251 will now be described.

A support or bracket 253 is fastened to the inner wall of the tube 42. This may be accomplished by the aid of several radial projections 254 which have exterior surfaces contacting the interior surface of tube 42; and cap screws 255 may pass through the wall of the tube 42 to thread into these projections 254. The upper portion of the bracket 253 is formed as a boss 256, having an axis coincident with axis 10. The interior surface 257 of the boss is spherical, having its center on the point 252. Enclosed within the spherical socket thus formed is a universal block 258. This universal block has end surfaces in cooperative relation with the socket 257. It is constrained by appropriate pins to motion about two transverse axes intersecting at the point 252, and both nor-

mal to axis 10. One of these axes is formed by a pin 259 and passes through point 252. This pin may be appropriately restrained in boss 256 against axial movement, as by a slight peening over of its ends.

By the provision of this pin 259, motion of the block 258 is confined to angular motion about the axis 260 of this pin (Figs. 3, 6 and 43). The block 258 fits accurately within a slot 261 (Fig. 6) that is provided in the lower ball end 262 of the mast 251. The exterior spherical surface of the ball end 262 is likewise in contact with the socket 257. The ball end 262 is joined to the universal block 258 by the aid of a short cross pin 263, the axis of which intersects the axis 260 at the axis 10. The pin 263 is short enough so that it cannot interfere with rotation of the block 258 in socket 257, all as clearly shown in Fig. 6.

Accordingly any definite angular position of the mast can be secured with respect to the axis 10. A rotation of the universal block 258 about axis 260 as viewed in Fig. 6, causes movement of the mast angularly in the plane of the paper of Fig. 6. Additional movement of the mast 251 is permitted about the axis 260 of the pin 263, out of the plane of the paper. The combination of these two movements makes it possible to bring the axis of the mast to any desired position within limits prescribed by the design. Appropriate provisions for lubrication, including fitting 515, are indicated for the bearing surfaces of the pins 259, 263.

The ball end 262 is shown as integrally joined to the bottom of the mast 251. Furthermore, mast 251 is provided with an enlarged threaded portion 264 beneath which is a cylindrical portion 265. Lastly, interposed between the cylindrical portion 265 and the ball end 262, a narrow flange 266 is provided.

The cylindrical portion 265 is telescoped within a mast hub 267. It is held in the mast hub 267 by the aid of the nut 268 (Figs. 3, 5 and 6) which engages the threaded portion 264. The hub 267 is confined between the lower surface of the nut 268 and the upper surface of the flange 266.

A control ring 269 (Figs. 3, 5 and 6) is disposed externally of the tube 42, for cooperating with mast 251, and for determining the position of the mast axis. The manner in which this control ring is adjusted to cause a corresponding adjustment of the mast position will be described hereinafter. The upper surface 270 of the control ring is shown as slightly tapered or conical and forms a track for a plurality of conical rollers 271 (see particularly Fig. 5). The axes of these rollers each intersect at the point 252, corresponding to the point about which the mast 251 has universal motion. Furthermore, the conical surfaces of these rollers all have an apex at this same point 252. The corresponding conical surface 270 of the ring 269 likewise has its apex at this point 252.

The rollers 271 may be supported for free rotation by the aid of anti-friction bearings supported on the stub shaft studs 272. These studs 272 are appropriately threaded into the mast hub 267. Castellated nuts 273 may be provided to restrain the rollers 271 from axial movement with respect to the studs 272.

Due to the fact that the conical surfaces of the rollers 271 and of the ring 269 converge at the common point 252, tilting of the ring 269 in a universal manner about the point 252 causes a corresponding tilt of the mast 251. In other words, angular adjustment of the axis of ring

269 causes a corresponding angular adjustment of the axis of mast 251.

Accordingly in order to adjust the mast position it is sufficient to adjust the position of the ring 269 in a universal manner. This is accomplished by the aid of a gimbal ring structure now to be described.

At diametrically opposite points of the ring 269 are disposed the ears 274. These ears are provided with bearing apertures 275 having a common axis 276 that intersects the point 252. Accordingly, movement of ring 269 angularly about the axis 276 will angularly adjust the axis of the ring 269 with respect to the axis 10; this results in a corresponding adjustment of the mast position.

The pivotal support of the ears 274 is formed in a gimbal ring 277. This gimbal ring, as shown most clearly in Fig. 6 is of generally tubular form. At the left hand side, as viewed in Fig. 5, the tubular gimbal ring is flattened to form a standard 278 (see also Fig. 3). This standard 278 supports a threaded hub 279 through which a pivot screw 280 is threaded. This pivot screw has a cylindrical end engaging the bearing surface 275 of the left hand ear 274 as viewed in Figs. 3 and 5. The pivot screw 280 may be maintained in proper position as by the aid of the check nut 281.

At the right hand end, the gimbal ring 277 is bent, to form a downwardly extending portion 282. To this portion are attached the operating arms 283. The manner in which these arms are operated will be described hereinafter.

The pivot screw 284 for the right hand ear 274 is supported in a bracket 285 welded or otherwise joined to the top of the extension 282.

There has now been described the mechanism whereby the control ring 269 may be tilted about the axis 276. By appropriate tilting of the gimbal ring 277 the ring can be given a tilt about the axis 286 (Figs. 5 and 6) which also passes through the point 252 and which is normal to the axis 276. Therefore by appropriate angular adjustment of the control ring 269 with respect to the axis of its pivot screws 280, and by appropriate angular adjustment of the gimbal ring 277 about axis 286, the angular position of the mast 251 may be adjusted as desired within the limits of the design.

The manner in which the gimbal ring 277 is supported may be best described in connection with Figs. 4, 5 and 6. At diametrically opposite sides of the ring 277, stub shafts 287 are inserted through the ring. They may be held in place as by welding or the like. The axes of these shafts fall along the axis 286. Reduced portions 288 of the stub shafts are journaled in the journal sleeves 289 mounted on stationary brackets. Accordingly in this structure the axis 286 is fixed with respect to the airplane.

The bearing sleeves 289 are supported upon appropriate standards. Thus the upper bearing 289 as seen in Fig. 5 is supported in a sheet metal standard 290 that widens toward the base and that is supported as by the screws 291 (Figs. 4 and 6) on the partition wall 62. The other stationary bracket 292 cooperating with the lower bearing sleeve 289 as viewed in Fig. 5, is similarly supported at its lower end on spacers 293 as by the aid of the bolts 294. The upper end of the bracket 292 is confined so as to lend substantial rigidity to the structure. For this purpose the upper end as shown at the right hand portion of Fig. 6, carries a sleeve 295 joined to the sheet

metal portions of the bracket 292, as by welding. Through this sleeve extends a bolt 296. This bolt is threaded into a circular nut 297 located in a cross aperture 298 formed in the wall of the hollow standard 23. If desired, a washer 299 may be interposed between the upper end of the sleeve 295 and the cooperating sloping surface 300 of the hollow standard 23.

10 Tilting of the gimbal ring 277 about the axis 286 causing a corresponding tilt of the axis 276 (Fig. 5) is accomplished by mechanism now to be described.

A pair of straps 283 (Fig. 5) is indicated permanently attached as by welding to the right hand side of the ring extension 282. These straps provide a clevis for pivotal connection to an eye 301. This eye 301 is formed at the upper end of a connecting rod or link 302 (Figs. 3, 4 and 7). This pivotal connection between the eye 301 and 15 the straps 283 may be conveniently provided by a bolt 303.

The lower portion of the link 302 terminates in an eye 304. This eye is pivotally connected to a sheave 305 by the aid of a bolt 306. This sheave 25 is mounted for free rotation about a bearing pin 307 that is appropriately fastened to the wall 308 of the hollow standard 23. The radial distance of the bolt 306 from the bearing pin 307 determines the throw of the link 302. Thus rotation 30 of the sheave 305 in a clockwise direction as viewed in Fig. 7 will elevate the link 302; and therefore the gimbal ring 277 will be rotated in a counterclockwise direction as viewed in Fig. 3. This corresponds to a tilting of the mast 251 toward the nose of the plane. Similarly, a counterclockwise rotation of the sheave 305 from the position of Fig. 7 will cause a downward movement of the ring 302 and a clockwise movement 35 of the ring 277 about axes 286. This corresponds to a movement of the mast 251 toward the tail of the plane.

40 This motion of the sheave 305 is accomplished by the aid of cable 539 which passes around the sheave 305 and which is controlled in a manner 45 to be hereinafter described.

Rotation of the control ring 269 about axis 276 causes corresponding movement of the mast 251 transversely of the longitudinal axis of the helicopter. This tilting motion is effected by the 50 aid of a link 309, which is shown in dotted lines in Fig. 3 and in section in Fig. 4. It is shown in full lines at the left hand end portion of Fig. 6. At its upper end (Figs. 5 and 6) it is provided with an eye 310 that is pivotally mounted on a pin 311. This pin 311 is attached to the bracket 312 carried by the depending flange of ring 269. Appropriate restraints, such as the castellated nut 313 may be used to confine the eye 310 against axial movement. A downward pull of the link 55 or rod 309 as viewed in Fig. 6, tilts the ring 269 about the axis 276 (Fig. 5). This in turn causes lateral movement of the mast 251. An upward movement of the rod 309 causes an opposite movement of the mast.

60 The lower end of the rod or link 309 terminates in an eye 314 (Figs. 3, 4 and 6). This eye is pivotally mounted in a clevis 315 formed at one extremity of a rocking lever 316. The lever 316 as shown most clearly in Figs. 3 and 4, is pivotally mounted by the aid of the bearing brackets 317 and 318 fastened to the upper side of the wall 62. Rocking of the lever 316 is accomplished by the aid of a rod or link 319 (Figs. 3 and 7). This rod 75 319 has an eye 320 at its upper end pivoted in the clevis formed in the end of the rocking lever 316.

A pivot pin 321 provides the pivotal connection between the eye 320 and the lever 316. The lower end of the link 319 terminates in the eye 322. This eye 322 is mounted upon a pin 323 similar to pin 306, but carried by a control sheave 324, coaxial with sheave 305 and mounted on bearing pin 307. This control sheave 324 is arranged to be angularly adjusted by a cable 325. The control sheave 324 has a long hub 326, spacing it from the control sheave 305. The two sheaves are held in appropriate axial relationship on the pivot pin 307 by the aid of the nut 327 (Fig. 3).

Clockwise angular movement of the sheave 324 causes rod 319 to be pulled downwardly. This causes an elevation of the rod 309 and a consequent movement of the mast 251 toward the left of the plane. A counterclockwise angular adjustment of sheave 324 produces the opposite effect.

If desired, a sheet metal cable guide and guard may be provided for the sheave structure. Thus for example such a guide and guard 328 is shown as interposed between the head of the pivot pin 307 and the outer sheave 324. It has three arms 329, 330 and 331, extending inwardly toward the wall 308 and fastened thereto in any appropriate manner, as by the screws 332. Adjacent the lower edge of guide 328, an arm 331 carried by the member 328 may be turned inwardly and again upwardly as indicated at 333. This portion 333 is wide enough to overlap both of the grooved faces on the pulleys 305 and 324, and form a guard therefor.

Transmission mechanism for rotor drive

It has heretofore been mentioned that the rotary tube 42 is driven by the aid of the driving disk 66 (Fig. 3). The manner in which this disk is driven may be best explained in connection with Figs. 3, 27, 28, 29, 30 and 31. Although but one transmission mechanism is described in detail, the transmission mechanism for operating the rotor 9 is identical with that for operating the rotor 8, except that its direction of rotation is opposite to that of the direction of rotation of rotor 8.

In the present instance, the drive disk 66 (Figs. 3, 27 and 28) is provided with a plurality of crank pins 334 having axes parallel with the axis 10 of the rotor tube 42. These crank pins 334 are arranged near the periphery of the disk 66, and they are equiangularly disposed around the axis 10 of the drive tube 42.

As shown most clearly in Fig. 3, each of these crank pins 334 is provided with an enlarged collar 335. This collar is urged into tight contact with the lower face of the disk 66 as by the aid of the nut 336 that is threaded on the end of the pin 334. The lower extension 337 of the pin carries the inner race of a ball bearing structure 338. This ball bearing structure is held in place upon the crank pin as by the aid of the nut 339.

The outer race of the ball bearing structure 338 is accommodated in the apertured enlarged end 340 of a connecting rod 345, which is one of a series of rods 341, 344, 345 (Figs. 27, 28 and 29). There are as many connecting rods as there are crank pins 334: twelve being shown in this instance.

We can consider at the present time a single one of the connecting rods. Thus a connecting rod 345 extends obliquely between the driving disk 342 and the driven disk 66. Disk 342 is mounted for rotation on axis 343 and is generally similar to the driven disk 66. The manner in which the driving disk 342 is driven will be set

forth fully hereinafter. At the present time it is sufficient to note that the axis 343 of this disk is parallel to but spaced from the axis 10 of disk 66, and also that the opposite faces of these disks are spaced apart.

The connecting rod 345 which connects the driving disks 66 and 342 is necessarily oblique to both of these axes. At its ends it is provided with enlarged heads such as 340 (Figs. 3 and 27) and 346 (Figs. 28 and 31) that are pivoted upon the crank pins such as 334 and 347. The angular spacing and arrangement of the crank pins 347 on the driving disk 342 are the same as the angular spacing and arrangement of the crank pins 334 on the driven disk 66.

Conveniently the main portion of the connecting rod 345 is formed of a uniform round bar threaded in opposite directions at its ends, into the corresponding shanks 348 of the heads 340, 346. In this way the length of the connecting rod may be adjusted. It may be held in tightened position as by the aid of a nut 349 engaging the split threaded end 350 of the shank 348.

As in connection with the crank pins 334 on driven disk 66, the crank pins 347 are pivotally joined to the heads 346 by the aid of the ball bearing 351 (Fig. 31).

As the driving disk 342 is rotated in a counterclockwise direction (Fig. 28), the connecting rod 345 obviously imparts a similar and equal counterclockwise rotation to the disk 66. This driving effect is multiplied by the aid of the additional connection rods indicated in general by the reference character 341 in Fig. 29. These connecting rods do not interfere in the course of rotation, due to their obliquity to axes 10 and 343. This obliquity is such that when one connecting rod, such as 345, is above another, such as 344, as viewed in Fig. 28, there is a considerable vertical distance between them. This is apparent from Fig. 27, where the connecting rod 345 is substantially immediately above the lower connecting rod 344. The effective lengths of all of the connecting rods are necessarily equal, since those points on the disks 342 and 66 that correspond to the centers of the crank pins joined by a connecting rod, stay at a uniform distance apart as the disks 342 and 66 move in synchrony.

By the provisions of a plurality of connecting rods which are non-interfering, a substantially uniform driving torque can be transmitted between the driving disks 342 and the driven disk 66. There is no danger of there being a dead center position and the series of connecting rods 341, 344, 345 all extend through the outrigger 12 which is hollow to accommodate these connecting rods. This is indicated in Fig. 29. This figure also shows the streamlined contour of the outrigger.

In order to drive the right hand rotor 9 (Fig. 2) driving disk 352 (Figs. 27, 28 and 30) is provided, similar to the driving disk 342. This driving disk 352 may be joined as by the oblique connecting rods 353 with the driven disk of the right hand rotor 9.

Engine mounting and connections

The location of the engine for driving the driving disks 342 and 352 is indicated merely diagrammatically in Fig. 1 by the outline 354. The engine may be appropriately mounted in the rear of the pilot's seat 5. Provisions as usual may be made to cool the engine cylinders, either by an air draft, or by a water jacket.

The engine 354 is furthermore provided as is usual, with an appropriate flywheel and clutch mechanism that ultimately drives the hollow shaft 355 (Fig. 32). This shaft 355 is coupled, through an overrunning clutch 356 to a hollow rear drive shaft 357 (Figs. 30 and 32). The clutch 356 and the shaft 357 are at least partially covered by a sheet metal fire wall casing 358 (Figs. 30 and 32) attached in any convenient manner to a partition 520 in the fuselage 1. This fire wall casing 358 is shown as cooperating with a gear case extension 359 to form a substantially complete closure for the hollow drive shaft 357.

The drive shaft 357 is arranged to drive a pair of spiral gears 360 and 361 (Figs. 30 and 31) in opposite directions. For this purpose, these gears mesh with a hollow spiral pinion 362 (see also Fig. 32) that is directly connected to the drive shaft 357, as by the splines 363. The gears 360 and 361 are in axial alinement with the driving disks 342 and 352 respectively and are engaged in driving relation thereto in a manner to be later described.

The gears 360, 361 and 362 are housed in a gear casing comprising the separable halves 364 and 365. These halves are joined together by the aid of the bolts 366 that pass through the edge flanges 367. The lower housing member 364 and the upper housing member 365 have intermediate portions 368 and 369 forming a tubular housing for the spiral pinion 362. Strengthening ribs, such as indicated at 370, 371 (Figs. 30 and 31) may extend between the tubular parts 368, 369 and the other parts of the housing.

The complete gear housing 364 and 365 is shown as supported upon channel beams 372, 373 (Figs. 27, 30 and 31) that extend in a direction generally parallel with the axis of the engine driving shaft 357.

Provisions may be made for supplying lubricant or grease inside the gear housing 364, 365, as by the aid of a filler pipe 374 shown in the upper right hand portion of Fig. 30, and closed as by a threaded plug 520.

By reference to Fig. 32, the manner in which the driving pinion 362 is supported may be described. It is appropriately supported in ball bearing structures 375 and 376 disposed at opposite sides of the cylindrical housing 368 and 369. The outer races 521 and 522 of these structures may be threaded into the sleeve 368, 369 (Figs. 30 and 32). Escape of lubricant out of the housing may be prevented by the aid of a resilient ring 377, such as synthetic rubber, fastened to the left hand portion of the pinion 362 and contacting with a stationary ring 378. Egress of lubricant from the right hand side of the pinion 362 is prevented by the provision of a wall 379 closing the right hand end of the outer race 522. A plug 523 to close the right hand end of pinion 362 may be appropriately fastened therein. Thus lubricant can be excluded from the hollow interior of pinion 362. Lubricant is hindered from moving to the left along rear drive shaft 357, by the aid of an oil seal 525 formed of closely spaced opposed annular ribs on ring 378 and pinion 362.

As indicated most clearly in Figs. 30 and 31, the driving pinion 362 is in mesh with the teeth on the gears 360 and 361. These teeth in the present instance are shown as formed on separate rings such as 380 that are attached as by the rivets 381 to the respective wheel spiders.

Since the driving connection between the gear

wheel 360 and driving disk 342 is identical with that between gear wheel 361 and driving disk 352, it is necessary to describe only the connections between the gear wheel 360 and the driving disk 342.

A tubular shaft 382 (Figs. 30 and 31) is supported by appropriate lower and upper ball bearing structures in the gear housing 364 and 365. Thus the lower end of the shaft 382 carries a tapered cap 383 ending in a hollow reduced cylindrical portion 384. This reduced portion carries the inner race of the radial and thrust ball bearing structure 385. The outer race of the ball bearing structure is carried in the standard 386 shown as integrally joined to the lower housing 364. This standard 386 may be provided with a downwardly extending threaded opening 387 that may be closed by pipe plug 388. Removal of the pipe plug 388 permits draining or cleaning out of the gear casing as desired.

The tubular shaft 382 adjacent its upper end has a flange 389 upon which is seated the inner race of a ball bearing structure 390. The outer race of this ball bearing structure is accommodated in the standard 391 joined to the upper casing half 365.

The tubular shaft 382 extends beyond the casing 365, its upper end being plugged by a plug 392.

The gear spider 360 is appropriately splined to the shaft 382, splines 393 for this purpose being indicated in Fig. 31. These splines are formed on the inner periphery of the gear hub 394. This hub 394 at its upper end abuts the lower side of the flange 389. Its lower end is tapered to accommodate a taper wedge ring 395. This taper ring 395 is urged upwardly to tighten the gear spider 360 as by the castellated ring nut 396.

The driving disk 342 is provided with a hub 397 which is splined to the upper end of the shaft 382, exterior of the gear casing. The lower end of this hub abuts a shallow shoulder and overlies the inner race of ball bearing structure 390. The upper end of the bore through the hub 397 is tapered to accommodate the wedging taper ring 398. This tapered wedging ring 398 is urged into position by the castellated ring nut 399.

The spiral pinion 362 drives both of the gear wheels 360 and 361 at a greatly reduced speed; this reduction may be such that if the engine speed is about 3300 R. P. M., the driving disks are rotated at the rate of about 480 R. P. M. Furthermore, the drive between gears 360, 361 on the one hand, and the pinion 362 on the other hand, is reversible. Accordingly, in the event that the engine should stall, the rotors 8 and 9 (Fig. 2) are allowed to rotate freely, due to the reaction of the air load. The overrunning clutch 356 (Fig. 32) ensures that any restraint on the drive shaft 355 will be ineffective to place a restraint on the shaft 357, driven in such cases by the pinion 362.

Control mechanism for adjusting position of mast in fore and aft directions

Fore and aft movement of the axis of mast 251 as heretofore explained is accomplished by the aid of the gimbal ring 277. By tilting the gimbal ring 277 about the axis 286 (Figs. 5 and 33), the control ring 269 is correspondingly tilted. This effect is diagrammatically illustrated in Fig. 33 which shows the control sheave 305

and the connecting rod or link 302 in operative relationship to the ring 277.

A corresponding mast 400, gimbal ring 401, control ring 402, link or rod 403 and sheave 405 are utilized in connection with the right hand rotor structure (Fig. 33). The mode of operation is identical and further description thereof is unnecessary.

The two sheaves 305 and 405 are interconnected with the flexible cable 539. By the use of appropriate guide pulleys 406, the control cable 539 can be so arranged that movement of the cable is under the control of the operator in the airplane. The control lever 407 for this purpose as indicated (Figs. 1 and 33) is so arranged that it may be readily grasped by the pilot and when moved in a direction forward or rearward of the fuselage, the masts 251 and 400 will be simultaneously and equally moved forward by an amount corresponding to the adjusted position of the control lever 407.

For this purpose the control cable 539 is joined to a control sheave segment 408. This segment is pivoted in a clevis 409 forming a stationary part of the apparatus. As the sheave 408 for example is rotated in a counterclockwise direction as viewed in Fig. 33, the cable 539 will be pulled in the direction of the arrows 410. It may readily be seen by the aid of the diagram of Fig. 33 that this pull causes an equal upward movement of the rods or links 302 and 403, causing an equal angular fore and aft displacement of the masts 251 and 400, to bring the ball ends of the masts forward.

Fore and aft movement of the control lever 407 is utilized to cause this rotation of the control sheave 408. Thus a forward movement of the control lever 407 will cause a forward movement of the masts 251 and 400, which operate the ailerons so as to depress the nose and elevate the tail, as heretofore explained.

The control lever to accomplish this purpose is arranged to be pivoted in a clevis 411, formed on a bracket 412. This bracket in turn is shown as integral with a hollow shaft 413. This hollow shaft is appropriately journaled in the stationary standards 414 and 415. Through the hollow shaft 413 extends a link or rod 416. At its forward end this rod 416 is pivotally connected by the aid of the clevis 417 carried by the lower end of the lever 407. At its aft end the rod 416 is provided with an enlarged cylindrical portion 419 in which there is an annular groove 418 (see also Fig. 34). Engaged in the groove 418 are the cylindrical ends of the screws 420. These screws 420 are supported in the opposite arms of a fork 421 mounted on the end of the arm 422. This arm 422 is joined to the control sheave segment 408.

A forward movement of the control lever 407 causes a corresponding rearward thrust upon rod 416. This in turn rotates control sheave segment 408 in a direction to move the cable 308 as indicated by the arrows 410.

The control lever 407 may be moved so as to rotate the hollow shaft 413 and the connecting rod 416 to perform another control function that will be described hereinafter.

However, such rotation does not affect the control mechanism illustrated in Fig. 33, since the ends of screws 420 continue to remain in operative engagement with the groove 418, independent of the rotation of the shaft 413 and the rod 416 in the standards 414 and 415.

Control mechanism for adjusting position of mast in lateral directions

This control mechanism is diagrammatically illustrated in Fig. 35. The same control lever 407 is utilized, but in this case this control lever is oscillated about the axis of the hollow shaft 413. Since it is coupled to the shaft 413 by the aid of the bracket 412, the manual force employed to move the lever 407 in a lateral direction will cause a corresponding rotation of the hollow shaft 413.

The control cable 325 in this instance extends around the sheave 324 (Figs. 3 and 7) as well as a similar sheave 541, associated with the control of the mast 400. Angular motion of the sheave 324 in the direction of the arrow indicated in Fig. 35 and a similar angular rotation of the sheave 418 will cause a tilting of the control rings 269 and 402 about the axes 276 and 540. This as explained heretofore, results in the corresponding lateral movement of the masts 251 and 400.

Idler rollers 542 are appropriately disposed in the airplane to lead the cable 325 to a control sheave 543. The cable 325 is fastened to the control sheave, which is mounted directly on the hollow shaft 413.

Accordingly rotation of control lever 407 in a lateral direction will cause a similar motion of the masts 251 and 400.

By a combination of the forward and aft motions of the control lever 407 and lateral motions thereof, the angular positions of the masts 251 and 400 may be determined. The control lever 407 thus controls banking or rolling, as well as the longitudinal pitch of the airplane.

Pitch control mechanism

Figs. 36 to 39 inclusive illustrate the manner in which the control sheave 170 (Figs. 3 and 4) may be angularly adjusted for simultaneously adjusting the position of all of the blades on the rotor 8. This mechanism also adjusts by an equal amount the angular position of the control sheave 544 associated with the other rotor 9.

In Fig. 36 the yoke 148 is illustrated joined to the shaft 160 of the sheave segment 170 by the aid of the crank 159 and link 155. An entirely similar mechanism is illustrated for the right hand rotor 9.

In this instance control of the pitch is manually effected by the aid of a lever 424 (Figs. 1, 36 and 37). This lever is arranged to be operated by the pilot seated in seat 5. In order to decrease the pitch of the blades the lever 424 is swung forward about the axis of a pivot pin 425. This pin is supported in the arms 426 of a bracket 427. A rearward movement of the lever 424 about the axis of the pin 425 causes an increase in the pitch of the rotors.

Provisions are made to maintain the pitch of the rotors in adjusted position without the necessity of holding the lever 424 by hand. For this purpose a notched segment 427 is provided. Cooperating with the notches in the segment is a retractable detent 428 operated in the usual manner, as by the auxiliary lever 429 pivoted on the lever 424. If desired, a tension spring 430 may be used urging the lever 424 toward pitch decreasing direction.

A forward movement of the lever 424 causes a pull to be exerted on the control cables 431 and 432 respectively connected to the sheaves 170 and 544. Appropriate guide pulleys 433 may be provided as needed for these cables. In order to exert this pull, the cables 431 and 432 are led over

the idlers 434 and 435 (see also Fig. 37) mounted upon the pivot pin 425. Thence the cables 431 and 432 are led respectively around the idler sheaves 436 and 437 carried at the lower extremity of the lever 424. Thence the cables 431 and 432 pass around additional idlers 438 and are finally attached to a sheave 439 (Figs. 36 and 39). This sheave is shown as pivotally mounted by the aid of the standard 440.

We may consider for the present that the sheave 439 is restrained against rotation. Accordingly when the lever 424 is moved forwardly or in a counterclockwise direction as viewed in Fig. 36, the cables 431 and 432 are pulled downwardly by the action of the idlers 436 and 437 on the cables. Accordingly the yokes 148 and 423 are pulled downwardly by the link mechanisms illustrated and the pitch of the rotors is thereby decreased. A rearward movement of the lever 424 causes a corresponding increase in the pitch of the rotors.

By the mechanism just described, it is possible equally and simultaneously to adjust the pitch of the rotors as may be required during flight to compensate for changes in throttle setting or inclination of flight path. At times, however, it may be necessary or desirable to make the pitch of one rotor greater than the pitch of the other so as to make the airplane fly in a curved path; or at times it may be desirable to minutely adjust the pitch of one rotor relative to the other in order to exactly balance the torque reactions so as to make the airplane fly in a straight path.

This can be accomplished by rotation of the sheave 439. Movement of the sheave in a counterclockwise direction as viewed in Fig. 36 will cause a pull on the cable 432 and a corresponding slackening of the cable 431. The resultant effect is that the pitch of the rotor 9 is decreased while the pitch of rotor 8 is increased. A clockwise rotation of the sheave 439 will increase the pitch of rotor 9, and decrease the pitch of rotor 8.

Even a slight angular motion is sufficient for purposes of control. This slight angular motion may be effected by the aid of a hand knob 441 (Figs. 1, 36 and 38). This hand knob may be conveniently mounted upon a wall or panel 442 within reach of the pilot. This knob 441 serves to rotate a lead screw 443 that is threaded in a square nut 444 (Figs. 36, 38 and 39). This square nut 444 is pivotally mounted in the arms 445 joined to the sheave 439. Rotation of the lead screw 443 causes advance or retraction of the nut 444 and a corresponding rotation of the sheave 439.

In order to permit free alignment of the axis of the lead screw 443 with the axis of the nut 444 as rotation of the sheave 439 imposes a change on the position of the nut, the lead screw 443 is mounted on a transverse axis. For this purpose a bearing sleeve 446 is provided for the shank of the lead screw 443. This sleeve 446 is provided with radially extending pivot pins 447 having an axis parallel with the axis of the pivot pins 448 of nut 444. The pins 447 are pivotally mounted in the brackets 449 attached to the wall 442. A collar 450 on the lead screw 443 confines the lead screw 443 against axial movement with respect to the bearing bushing 446.

General

As in good practice in airplane design, it is desirable to lock all fastening means against loosening, as by lock wires, cotter pins, or the like. Such locking devices have not been indicated but

are intended to be used wherever needed. Also all metal parts may be made corrosion resistant, as by appropriate plating or by appropriate choice of materials.

Summary

By means of the arrangements and mechanisms hereinabove described, a helicopter may be made to respond instantly and positively to the pilot's manipulation of the controls. In the arrangement described, all control provisions are incorporated in the design and function of the rotor blades, which are controllable in such a way that in flight they may always have sufficient speed to insure adequate control with or without power. Furthermore, the control motions required are natural and instinctive since movement of the control lever 401 operates the ailerons in such a manner as to set up air forces that tend to tilt the craft in the direction of the motion applied to the control lever. These air forces, furthermore, are carried through the structural members of the rotor blades, hubs, and rotor support outriggers directly to the fuselage structure, as contrasted to the more common arrangement in which the rotor blades are hinged to the rotor hubs, with a resulting lag and lack of force in the control response.

In a divisional application, Serial Number 11,652, filed February 27, 1948, entitled Multiple rotor helicopter, the features incorporating the double rotor construction and its drive are claimed.

What is claimed is:

- 35 1. In a control system for a rotor blade having a controllable aileron thereon, a pivoted arm carried by the blade and operatively connected to the aileron, a tension element for exerting a pull to move the arm angularly, and a weight carried by the arm and creating a centrifugal force due to rotor rotation, said force exerting a torque about the pivot axis of the arm opposing that due to the pull on the tension element, the weight being in such position with respect to the arm pivot that the torque arm measured from said pivot to the direction of the centrifugal force decreases for an outward motion of the tension element from the neutral position of the aileron, and increases for an inward motion of the tension element from said neutral position, the decrease per unit of such outward motion being greater than the increase per unit of such inward motion.
2. In a control system for a rotor having a plurality of blades extending radially from the axis of rotor rotation, each of said blades having an aileron capable of movement in either direction from a neutral position, flexible tension elements respectively operating said ailerons and extending radially inwardly of the rotor, means connecting the elements, and capable when displaced from the neutral position, of causing a displacement of said elements in succession during a rotation of said rotor, weights respectively associated with each tension element for creating a centrifugal force opposing said pull and maintaining said elements under tension, the position of said weights with respect to the said elements being such that upon a departure from neutral 55 of said connecting means, the resultant of the centrifugal forces of all of the weights is in a direction to urge the flexible elements toward neutral position.
3. In a control system for a rotor blade having a controllable aileron thereon, a pivoted arm car-

ried by the blade and operatively connected to the aileron, a tension element for exerting a pull to move the arm angularly, and a weight carried by the arm and creating a centrifugal force due to rotor rotation, said force exerting a torque about the pivot axis of the arm opposing the torque created by the pull on the tension element, the weight being in such position with respect to the arm pivot that the torque arm measured from said pivot to the direction of the centrifugal force decreases for an outward motion of the tension element from the neutral position of the aileron, and increases for an inward motion of the tension element from said neutral position, the decrease per unit of such outward motion being greater than the increase per unit of such inward motion.

4. In a control system for a rotor having a plurality of blades, each blade having a controllable aileron, a mast having an axis that coincides with the axis of the rotation of the rotor at least at one point, and means for angularly adjusting the position of the mast, comprising a pair of non-rotary rings, having transverse tilting axes, intersecting at said one point, means forming a guide surface, the degree and direction of tilt of said surface being a function of the positions of the rings about their tilting axes, and a follower carried by the mast and cooperating with said guide surface.

5. In a control system for a rotor having a plurality of blades, each blade having a controllable aileron, a mast connected at its end to said ailerons, having an axis that coincides with the axis of rotation of the rotor at least at one point, a universal joint supporting said mast, and means non-rotary with respect to the rotor, for adjusting the angle of the mast axis with respect to the axis of rotor rotation, comprising a pair of non-rotary rings, having transverse tilting axes, intersecting at said one point, means forming a guide surface, the degree and direction of tilt of said surface being a function of the positions of the rings about their tilting axes, and a follower carried by the mast and cooperating with said guide surface.

6. In a control system for a rotor having a plurality of blades extending radially from the axis of rotor rotation, each of said blades having an aileron capable of movement in either direction from a neutral position: pivoted arms respectively carried by the blades and operatively connected to the respective aileron for moving the aileron out of neutral position in either direction; tension elements respectively for each aileron for exerting a pull to move the respective arm angularly; and weights respectively carried by the arms

and creating centrifugal forces due to rotor rotation, said forces exerting torques respectively about the pivot axis of the corresponding arm, and opposing the torques created by the pull on the corresponding tension element, the weights being in such position with respect to the arm pivots that the centrifugal force due to a weight creates torques about the corresponding pivots, said torques opposing the torques due to the pull of the tension elements, and the torque arm measured from the pivot of the corresponding arm pivot to the direction of the centrifugal force decreases for an outward motion of the tension member from the said neutral position, and increases for an inward motion of the tension member from said neutral position, the decrease per unit of such outward motion being greater than the increase per unit of such inward motion.

7. In an aileron control system for a rotor having a blade carrying an aileron: a pivoted member having a pivot fixed with respect to the blade, and connected to the aileron for moving it; a pulling element extending lengthwise of the blade for causing angular movement of the member; centrifugally operated means for opposing the pull of said element; and a flat spring member having one end anchored to the aileron, and the other end anchored with respect to the blade, whereby said spring is twisted when the aileron is moved, the flat spring exerting a force opposed to the pull of said element.
